W. M. MANGUM

SCREEN

Filed March 17, 1922

FIG-1.

FIG-2.

Inventor:

Wiley M. Mangum

UNITED STATES PATENT OFFICE.

WILEY M. MANGUM, OF PURDY, VIRGINIA.

SCREEN.

Application filed March 17, 1922. Serial No. 544,656.

To all whom it may concern:

Be it known that I, WILEY M. MANGUM, a citizen of the United States, and a resident of Purdy, in the county of Greensville and 5 State of Virginia, have invented new and useful Improvements in Screens, of which the following is a specification.

This invention relates more especially to screens for windows, doors and the like, 10 which are used to protect the same, when open, against flies, mosquitoes and the like, although my improvements may be utilized in a screen for any place whatever to permit circulation and protect against insects 15 of any kind.

The objects of the invention are to secure an improved construction by which flies and the like are permitted to pass through the screen out of the room or apartment 20 to be protected and are prevented from passing in; to secure such a screen which appears when looked through from either side to be of a single thickness of screening; to provide such a screen with peripherally 25 projecting marginal portions of screening which have their outer edges even or both terminating at the end of the passage between them; to space said outer edges, and the outlet of the passage, from the frame 30 so as to ensure that the fly or other insect has only one edge of screen to stand upon in attempting to enter through the passage; to thus render such entrance impossible; to provide for this purpose a screen frame 35 having a peripherally continuous surface upon which the screening forming one wall of the passage can be secured and thus enable the screening to be applied in one large piece and four strips corresponding to the 40 four edges of the screen; to thus simplify, expedite and cheapen the manufacture of the screens and to increase their efficiency by providing a continuous exit slot for the entire periphery of the screen, and to obtain 45 other results and advantages as may be brought out by the following description.

Referring to the accompanying drawings, in which the same reference characters designate corresponding and like parts,

50 Figure 1 is an outside view of one form

of a screen of my improved construction, and

Figure 2 is a section of the same on line 2-2 of Fig. 1, looking in the direction indicated by the arrow.

55

In the specific embodiment of the invention shown in said drawings, 1 and 2 indicate the side pieces of the screen frame, and 3 and 4 the top and bottom pieces, said pieces being made of any suitable and well 60 known material and secured together in any suitable and well known manner for application to a window or similar opening as is common in the art. In the particular screen shown, a strip 5 is provided at one side 65 edge of the screen, hinged to the side piece 2 by hinges 6, 6 and thus adapted to partially fold for insertion of the screen beneath a window sash, the strip 5 being held extended as shown in the drawing by a 70 button 7. This, however, is not essential to the present invention, and the screen may be applied to a window or other opening in any manner.

I have shown in said drawing a raised rib 75 8 at the outside of the screen frame and adjacent to the opening through the same, this rib providing an inner screen supporting surface upon which are tacked strips 9 of screening, one for each edge of the 80 screen; these strips are preferably flush with the rib 8 at its side next the frame opening, and project beyond the rib at its opposite side a suitable distance to necessitate a fly crawling up the strips away 85 from the rib 8 to reach said projecting edge of the strips, as shown in Figure 2 at reference numeral 13.

Upon the said strips 9 are placed at suitable intervals blocks 10 which are wedge 90 shaped transversely of the rib 8 with their thicker ends next the frame opening, said blocks being secured in place by nailing to the rib 8 and providing outer screen supporting surfaces. The main screening 11 of 95 the screen is then laid on the said blocks 10 and secured thereto by tacking, said screening 11 being of such size and dimensions that its marginal portion 12 extends beyond the blocks 10 a distance equal to 100

the projection of the strips 9 at 13. Furthermore, by reason of the said tapered blocks 10 said marginal portion of the main screening 11 converges away from the frame opening toward the strips 9 to form a tapered passage between, the edges of which passage walls away from the frame opening are substantially even as shown in the drawings, that is to say, both walls terminate in a plane substantially perpendicular to the plane of the screen, so that a fly or the like must stand upon said edges or one of them to enter between them.

Preferably the inner and outer screen supporting surfaces, and therefore also the rib 8 and blocks 10, have their corresponding lateral edges in the case of the surfaces and their corresponding sides in the case of the rib and blocks, in the same plane perpendicular to the plane of the screen frame. That is to say, the side of the rib 8 and ends of the blocks 10 next the frame opening are in the same perpendicular plane, at a given point, and the same is true at the opposite side of the rib 8, as clearly shown in Figure 2. The effect of this is that when the screen is viewed as in Figure 1, said lateral sides or lateral edges of the screen supporting surfaces toward the frame opening coincide, and same is true of the opposite lateral edges away from the screen opening; therefore practically nothing but the outer screening is seen and the visional effect is not much different from an ordinary screen.

When the screen is placed in a window, it will be understood that only a single thickness of screening is looked through in either direction, and from the inside of the room there is hardly anything to be seen except the single thickness of screening. Any flies gathering on the inside of the screen will tend to crawl toward the edge of the screen and passing between the blocks 8 will escape through the tapering passage between the marginal portions of screening. On the other hand, any flies on the outside of the screen, if they walk to the extreme edge of the main screening 11, will have to turn sharply over said edge to enter the small end of the tapered passage, which they are not at all likely to do, in fact, it has been found that none will enter in this way.

It will be seen that by my invention I provide a tapered passage between two outwardly projecting marginal portions of screening which not only terminate evenly at their ends but also are spaced from other parts of the screen, so that a fly to enter must crawl up the outside of one of the walls of the passage and turn sharply over its edge into the small end of the passage. This may be secured in many other ways than the one specifically shown for purposes of illustration, and therefore I do not wish to be un-

derstood as limiting myself except as required by the following claims when construed in the light of the prior art.

Having thus described the invention, what I claim is:

1. In a screen, the combination of a frame, a piece of screening over the opening of said frame and spaced from the frame with its marginal portion projecting peripherally beyond said opening, and a strip of screening between said frame and piece of screening adjacent the opening of the frame in such spaced relation to the main screening as to permit a fly to pass therebetween from the opening of the frame, the edge of said strip next the opening of the frame forming a closure therewith and the edge away from the frame opening being free and spaced from the frame and terminating substantially flush with the edge of the marginal portion of the main screening, whereby a fly or the like must stand on the said edges to enter between them.

2. In a screen, the combination of a frame, means at the outer side of said frame and adjacent its opening providing screen-supporting surfaces in spaced planes which converge outwardly and peripheral outlets between said planes, and inner and outer screening secured to said surfaces with marginal portions projecting therebeyond away from the frame opening in spaced relation to the frame to form an exit for flies or the like, the outer screening closing the opening of the frame and the inner screening leaving it open both centrally and peripherally to said outlets.

3. In a screen, the combination with a frame having at its outer side and adjacent its opening a screening surface, blocks projecting from said surface and providing other screening surfaces transversely similar to the first-mentioned surfaces, said screening surfaces converging outwardly, and screening secured on said surfaces and projecting outwardly therefrom with their edges free from the frame and forming a tapering exit passage from the frame opening, the outer screening closing the frame opening and the inner screening leaving it open.

4. In a screen, the combination with a frame having at its outer side and adjacent its opening an inner screen-supporting surface, blocks projecting from said surface and providing an outer screen-supporting surface spaced from the first-mentioned surface and coextensive therewith transversely of the frame in its plane, and inner and outer screening spaced from each other secured to said surfaces and projecting beyond the same away from the opening and terminating in edges free from the frame, the outer screening closing the frame opening

and the inner screening leaving it open and forming with the outer screening an exit passage from said opening.

5. In a screen, the combination of a frame providing at its outer side and adjacent its opening spaced screen-supporting surfaces which have their corresponding lateral edges lying in the same plane perpendicular to the plane of the frame, and inner and

outer screening spaced from each other secured to said surfaces with marginal portions projecting therebeyond in spaced relation to the frame and terminating substantially even with each other and with the passage between them, the outer screening 15 closing the frame opening and the inner screening leaving it open.

WILEY M. MANGUM.
